(57) **CLAIM**

The ornamental design for a phone case with belt clip, as shown and described.

DESCRIPTION

FIG. 1 is a front, right-side, and top perspective view of a phone case with belt clip showing my new design; FIG. 2 is a rear, left-side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear, left-side, and bottom perspective view thereof wherein the belt clip is shown in an open configuration; and,

FIG. 10 is an enlarged view of portion 10 shown in FIG. 2. The dot-dash broken lines in FIGS. 2 and 10 form no part of the claimed design and delineate a portion of the claimed design that is shown on an enlarged scale in FIG. 10. The dashed broken lines throughout the drawing figures form no part of the claimed design and depict portions of the phone case with belt clip that form no part of the claimed design.
